F. M. WHITNEY,
END RING FOR SQUIRREL CAGE WINDINGS,
APPLICATION FILED MAY 28, 1914.

His ATTORNEY.

UNITED STATES PATENT OFFICE.

FRANCIS M. WHITNEY, OF SAN DIEGO, CALIFORNIA, ASSIGNOR TO GENERAL ELECTRIC COMPANY, A CORPORATION OF NEW YORK.

END RING FOR SQUIRREL-CAGE WINDINGS.

1,215,088.

Specification of Letters Patent. Patented Feb. 6, 1917.

Application filed May 28, 1914. Serial No. 841,635.

To all whom it may concern:

Be it known that I, FRANCIS M. WHITNEY, a citizen of the United States, residing at San Diego, in the county of San Diego, State of California, have invented certain new and useful Improvements in End Rings for Squirrel-Cage Windings, of which the following is a specification.

My invention relates to squirrel cage 10 windings for dynamo electric machines, and more especially to an end ring construction for such windings and the method of applying the same.

The usual end ring constructions are of 15 such form that they require special tools either for their application or their manufacture. It is desirable, however, that the construction of the end ring for a squirrel cage winding should be such that it can be 20 easily repaired or replaced by means of ordinary tools and from easily obtained material. Such a need is especially apparent in the smaller sizes of induction motors with squirrel cage secondaries.

25 The object of my invention is, then, to provide a novel construction of an end ring for a squirrel cage winding, and also a novel method of securing the same to the bars of the winding, which is simple, efficient and 30 capable of being carried out with the aid of ordinary tools and common materials.

My invention will be more readily understood by reference to the accompanying drawing, in which:

35 Figure 1 is a radial section of the rotor of an induction motor showing the method of application of my end ring construction at the right, and the finished product at the left.

40 Fig. 2 is a fragmental end view of the finished construction with a portion of the outer annular member broken away.

In the construction shown, the rotor 1 is provided with the customary laminated core 45 2 in which are placed the conductor bars 3. The bars 3 are shown as of substantially rectangular cross-section, and while this is not absolutely essential, it will be preferable for the application of my invention.

50 At the left side of Fig. 1 the completed end ring is shown to consist of a flanged annular member 4 and a similar flanged annular member 5, engaging the inner and outer peripheries of the conductor bars, one of the 55 annular members forcing the bars into en-

gagement with the other annular member, whereby good electrical contact is obtained between the bars and the end ring. These annular members are preferably formed of sheet copper and may be conveniently made 60 by the use of a spinning lathe. I have found that for end rings to be applied to induction motors of 10 or 20 H. P., sheet copper of about #16 gage is suitable.

The annular member 4, comprising a 65 transverse flange 6 and a radial flange 7, is made of such a diameter that it will exactly fit the inner periphery of the conductor bars. When first placed in position it is pushed back from the ends of these bars, and the 70 bars then bent toward the member 4, as indicated at 3', by being lightly tapped with a hammer. By these processes, it will be seen that the diameter of the outer periphery of the bars is slightly reduced. The other 75 annular member 5, similarly constructed with a transverse flange 8 and a radial flange 9, is made of such a size that the inner diameter of the flange 8 is slightly less than the normal diameter of the outer periphery of 80 the bars. When the diameter of said outer periphery has been reduced in the manner described, however, this annular member 5 will exactly fit over the outer ends of the bars. If, now, the member 4 is forced out- 85

wardly toward the ends of the bars until it is in the same plane as the member 5, it will be seen that the bars will be forced by flange 6 into engagement with flange 8 and consequently will be tightly gripped between 90 the transverse flanges 6 and 8, because the difference of the radii of the engaging surfaces of these flanges before their application to the bars 3 is slightly less than the radial thickness of the bars. The process 95 of forcing the member 4 outwardly may be carried on in any convenient manner, as by inserting some blunt ended tool between the conductor bars and against the flange 7 and then lightly tapping the tool with a ham- 100 mer. This process will, of course, be carried on progressively around the circumference of the rotor. Still another manner of forcing out the member 4 is illustrated at the right side of Fig. 1, where a clamp 10 en- 105 gages the radial flanges 7 and 9. By providing a suitable number of such clamps and tightening them in unison, the member 4 would be drawn outwardly until it is con- 110 tinuous with the member 5.

By this means I have provided a simple construction of end ring which may be easily manufactured and applied by the use of my novel method with the ordinary tools to be found in a repair shop. The end ring will be frictionally held on the conductor bars, and the application of any solder is unnecessary, in order to secure good electrical contact therebetween. If desired, however, I may fill the spaces between the conductor bars within the flanges 6 and 8 with melted solder or melted brass. Such an artifice will add to the rigidity of the construction and the conductivity of the ring. An inspection of the left hand side of Fig. 1 will show that if the flanges 6 and 8 of the annular members are made of equal widths, that of the member 4 will be slightly closer to the core 2 of the rotor. Consequently, if the rotor is placed on end in order to pour in the melted solder or brass, any surplus metal will flow over the outside.

I conceive that various modifications of the particular form of annular members are possible, as well as of the particular manner of bringing said annular members into the same plane, and I, accordingly, do not desire to be limited to the exact construction or method of application illustrated and described, but seek to cover in the appended claims all those modifications and equivalent constructions which fall within the true scope and spirit of my invention.

What I claim as new and desire to secure by Letters Patent of the United States, is:—

1. A squirrel cage winding comprising conductor bars of substantially rectangular cross section, and an end ring connecting said bars comprising two annular members each provided with a transverse flange, the flange on one of said members engaging one periphery of said bars, the flange on the other of said bars engaging the other periphery of said bars in substantially the same plane as said first mentioned flange and forcing said bars into engagement therewith, said annular members being also provided with radial flanges, one of which overhangs the ends of said bars and the other of which is contiguous thereto and in electrical contact therewith.

2. A squirrel cage winding, comprising conductor bars of substantially rectangular cross section, and an end ring connecting said bars comprising two annular members 55 each provided with a transverse flange, the flange on one of said members engaging the outer periphery of said bars, the flange on the other of said members engaging the inner periphery of said bars in substantially the 60 same plane as said first mentioned flange and forcing said bars into engagement therewith, said annular members being also provided with radial flanges one of which overhangs the ends of said bars and the other 65 of which is contiguous thereto and in electrical contact therewith.

3. The method of securing an end ring to the bars of a squirrel cage winding, which consists in placing an annular member in 70 engagement with one periphery of said bars away from the ends thereof, slightly bending the ends of said bars toward said annular member, applying another annular member to the other periphery of said bars, the 75 latter member having its engaging surface of a diameter slightly different from the normal diameter of the periphery of the bars to which it is applied, and then forcing the two members into substantially the same plane, 80 whereby the bars are tightly gripped therebetween.

4. The method of securing an end ring to the bars of a squirrel cage winding, which consists in placing an annular member 85 in engagement with the inner periphery of said bars, away from the ends thereof, slightly bending the ends of said bars inwardly, applying another annular member over the bent ends of said bars, the difference 90 in the radii of the engaging surfaces of said annular members being slightly less than the radial thickness of said bars, and then forcing the two members into substantially the 95 same plane, whereby said members are tightly held in engagement with said bars.

In witness whereof, I have hereunto set my hand this 19th day of May, 1914.

FRANCIS M. WHITNEY.
